(57) **CLAIM**

The ornamental design for a closure, as shown and described.

DESCRIPTION

FIG. 1 is a front isometric view of a first embodiment of a closure showing my new design with the closure in the closed condition, and the closure is adapted to be mounted on a bottle or other container (not illustrated);
FIG. 2 is a top plan view thereof;
FIG. 3 is a right side elevational view thereof;
FIG. 4 is a left side elevational view thereof; and,
FIG. 5 is a front elevational view thereof.
The undisclosed rear view is unornamented.
